UNITED STATES PATENT OFFICE.

OTIS A. MYGATT, OF NEW YORK, N. Y.

DESIGN FOR A REFLECTOR.

No. 37,985.

Specification for Design.

Patented May 1, 1906.

Application filed December 14, 1904. Serial No. 236,898. Term of patent 7 years.

To all whom it may concern:

Be it known that I, OTIS A. MYGATT, a citizen of the United States, residing at New York, in the county of New York and State of New York, have invented a new, original, and ornamental Design for Reflectors, of which the following is a specification, reference being had to the accompanying drawings, forming a part hereof.

My design relates to reflectors for artificial lights.

My reflector is composed of transparent glass.

The reflector is generally applied to incandescent electric lamps and is most frequently seen from below or from the interior.

The reflector in which my design is embodied is in form of the hollow frustum of a cone, with a collar at the top.

Figure 1 is a side elevation of a reflector embodying my design, so far as the same can be represented in a line drawing. Fig. 2 is an interior or bottom view of the same. Fig. 3 is a central section.

The top or collar of the reflector is smooth and rounded, as shown. The exterior of the body from the collar to the prismatic portion is of ground or frosted glass. The interior of the same portion of the reflector is smooth. Seen from without this part of the reflector is of the whitish color of ground glass. Seen from within, as in Fig. 2, this part of the body presents a brilliant reflecting-surface.

The exterior of the body from the frosted portion to the lower edge is covered with prisms integral with the body and arranged radially, as shown. These prisms are of clear

glass and seen from the outside appear brilliant or somewhat opaque, according to the angle from which they are viewed. The prisms terminate in a row of scallops, which present a bead-like appearance when seen from the front, as in Fig. 2, especially when illuminated.

The interior of the prismatic portion of the body is covered with prisms extending in concentric circles. These prisms present different appearances when seen from different directions, but a generally iridescent appearance.

As the glass is transparent the prisms on the outside of the reflector are visible from within, and vice versa, presenting a somewhat checkered appearance impossible to be shown in black and white; but viewed from the general direction of vision, as in Fig. 2, the interior of the reflector is much more brilliant than the exterior, especially when illuminated with an artificial light. From some angles or directions colored spectral or prismatic effects are seen in the glass.

I claim—

The ornamental design for a reflector composed of transparent glass, having a top collar, the upper external portion being frosted and the interior thereof smooth, the lower external portion being covered with radial prisms and the interior with prisms arranged in concentric circles, and the lower edge beaded.

OTIS A. MYGATT.
